UNITED STATES PATENT OFFICE.

SIMON W. WILKINS, OF ALTAMONT, KANSAS.

BED-LOUNGE.

SPECIFICATION forming part of Letters Patent No. 580,800, dated April 6, 1897.

Application filed November 29, 1895. Serial No. 570,506. (No model.)

To all whom it may concern:

Be it known that I, SIMON W. WILKINS, a citizen of the United States, residing at Altamont, in the county of Labette and State of 5 Kansas, have invented a new and useful Bed-Lounge, of which the following is a specification.

This invention relates to bed-lounges; and the object in view is to provide a lounge or 10 sofa constructed in such manner as to be easily and readily convertible into a bed of full length and width. The detailed objects and advantages of the invention will appear in the course of the ensuing description.

15 The invention consists in an improved combination lounge and bed embodying certain novel features and details of construction and arrangement of parts, as hereinafter fully described, illustrated in the drawings, and 20 finally pointed out in the claim.

In the accompanying drawings, Figure 1 is a perspective view of the improved bed-lounge, the same being unfolded and constituting a bed. Fig. 2 is an end view of the 25 same with the adjacent end pieces of the frames partially broken away to show one of the curved swing-arms and one of the balance-springs connected therewith. Fig. 3 is a perspective view of the device folded and 30 constituting a sofa or lounge. Fig. 4 is a vertical transverse section through the same with the mattress omitted, showing the relative positions of the swing-arms and balance-springs under such adjustment. Fig. 5 is a detail 35 perspective view of one of the swing-arms. Fig. 6 is an end view of the bed-lounge, shown partially open. Fig. 7 is a detail longitudinal section through one end of the lounge in its folded position.

40 Similar numerals of reference designate corresponding parts in the several figures of the drawings.

Referring to the drawings, 1 designates an open rectangular frame which constitutes the 45 main frame of the lounge or sofa proper. To this frame is added the usual upwardly-extending back 2, which may be suitably upholstered, as indicated at 3. The frame 1 is supported at its four corners upon legs 4 of 50 the proper height, the rear legs being preferably extended higher than the front legs to assist in supporting the back 2, and the front

legs being rounded off upon their front upper corners, as shown at 6, for the purpose of receiving and supporting the spring-arms of 55 the device, as will hereinafter appear. Within the open rectangular frame thus formed are secured a number of horizontal, longitudinal, and transverse wires 7 and 8, the longitudinal wires 7 being formed with arched 60 or upwardly-deflected portions which pass above and receive the transverse wires 8 in approximately the same plane with the main body of each longitudinal wire 7. At the intersections of the longitudinal and transverse 65 wires are located spiral bed-springs 9, one for each intersection, and these bed-springs have their lower coils interwoven with said longitudinal and transverse wires, so as to pass alternately above one and beneath the other, 70 as shown. These springs are interconnected by means of wires or ropes 10 and also compressed thereby to the desired extent, and the ends of said wires or ropes are secured to the side and end bars of the frame 1. 75

11 designates a longitudinal series of similar springs which are arranged upon the front bar of the frame 1, their object being to support the mattress and bedding at a point intermediate the springs of the lower section 80 and those of the upper section of the lounge when folded into the position shown in Fig. 1.

12 designates the upper section, which is also in the form of an open rectangular frame, similar in size to the frame 1 and provided 85 with a spring-bottom exactly similar to that above described in connection with the lower section. This upper section is upholstered in an appropriate manner similar to any ordinary lounge or sofa and is provided at one 90 end with a hinged head-rest 13, which is made hollow to form a pocket, the same being adapted to serve as a depository for a night-robe or other article. Within such pocket, when folded, is arranged a pillow-rest 14, the same 95 comprising a spring-frame, which is preferably made of wire and upholstered or covered with some light material. This pillow-rest serves as a prop for the pillow, giving to the same the desired cant, and also preventing said pillow from slipping off the end of the upper section. The upper section is provided along its front edge with a downward extension 15, which forms the front of the 100

lounge, and this front is braced with relation to the frame of the upper section by means of a pair of angle-irons 16, secured one to each end of said upper section, the 5 vertical arm of each angle-iron being secured to the downward extension or front 15 and the horizontal arm of said iron being secured to one of the end bars of the upper section in the manner shown. This construction 10 serves to brace the downward extension on the upper section and adapts the same to be used as the supporting-leg for said section when thrown into the position shown in Fig. 1. The upper and lower sections above de- 15 scribed are connected pivotally by means of a pair of swing-arms 17, which are made substantially S-shaped or in ogee form. Each of said arms is provided at each extremity with an outwardly-projecting stud or pivot 20 18, one of said pivots entering a socket in the end board of the lower frame 1 at a point between the transverse center thereof and the forward bar of the frame and the other pivot entering a socket in the frame of the 25 upper section at a point in proximal relation to the inner edge thereof. At a point intermediate its ends each of said ogee swing-arms is provided with an integrally-formed inward horizontal extension 19, and said extensions 30 are perforated to provide for the passage of screws or other suitable fastening devices which enter the opposite ends of a spacing-bar 20, preferably of wood. This spacing-bar serves to hold the swing-arms at the 35 proper distance apart and to preserve the proper engagement between the pivots of said arms and the sockets in the upper and lower frame-sections in which said pivots work.

40 Secured to the spacing-bar 20, adjacent to each end thereof, is a screw-eye 21, and from this screw-eye a balance-spring 22 extends to and connects with a pin or hook secured within the frame of the upper section at a point 45 near the outer or front end of said frame. By reason of the particular manner in which the swing-arms and upper section are connected and the disposition of the balance-springs 22 and their point of attachment with relation 50 to said swing-arms it will be seen that these springs will assist materially in returning the upper section from the position indicated in Fig. 1 to its normal position. (Indicated in Fig. 3.) It will also be noted that the inner 55 portions of the swing-arms rest upon the curved upper ends of the front legs of the lower section, and the outer ends of said arms curve beneath and receive the inner side edge of the upper section in such manner as to 60 form an effective support therefor and at the same time enable the upper section to be dis-

posed in a lower horizontal plane than has heretofore been possible in devices of this character. Extra transverse timbers 23 are secured to the upper extremities of the legs 65 inside of the end boards of the frame 1, so as to form pockets within which the swing-arms rest when the device is folded, as in Fig. 3, said extra timbers also serving to prevent lateral displacement of the ends of said arms. 70 Upon the spring-bottom of the lower section 1 is placed a mattress 24, of any usual or preferred material, and this mattress is provided upon that edge adjacent to the upper section when folded outward and downward with an 75 apron 25 of sufficient size to extend entirely over the upholstered top of the upper hinged section, the object being to protect the upholstering and preserve the good appearance of the same. When the device is no longer 80 needed as a bed, the hinged section is lifted by means of suitable handles or straps 26, whereupon the balancing-springs materially assist the swing-arms in returning said hinged section to its normal position. The mattress 85 24, together with its apron 25, is included within the space between the upper and lower sections provided for that purpose.

From the foregoing description it will be seen that a very simple, compact, and convenient combination lounge and bed is obtained in which a novel construction of devices provide for returning the hinged section with very slight exertion to its normal position, and these devices are arranged in such 95 manner as to leave the top of the main or lower section unobstructed for the reception of the mattress and bedclothes, &c.

Having thus described the invention, what is claimed as new, and desired to be secured by 100 Letters Patent, is—

In a bed-lounge, the combination with the main lower section, of a movable section, swing-arms arranged at or near the ends of said sections and pivotally connected to each 105 section, a spacing-bar rigidly connecting said swing-arms adjacent to their pivotal connection with the movable section, and a counter-balancing-spring connected at one end to said spacing-bar and at its opposite end to the 110 movable section, said spring being located at all times beneath the movable section, whereby the top of the main section is left free and unobstructed, substantially as described.

In testimony that I claim the foregoing as 115 my own I have hereto affixed my signature in the presence of two witnesses.

SIMON W. WILKINS.
